232,803

SPATULA FOR FILL-IN COMPOSITIONS Charles Kleiman, Highland Park, Ill., assignor to
Lake Chemical Co., Chicago, Ill.

Filed Jan. 22, 1973, Ser. No. 325,382

Term of patent 14 years

Int. Cl. D8—03

U.S. Cl. D8—45

FIG. 1FIG. 2FIG. 4FIG. 3FIG. 1 is a top plan view of a spatula for fill-in compositions showing my new design;

FIG. 2 is a side elevational view thereof, partly in section;

FIG. 3 is a right end elevational view of FIG. 1; and
FIG. 4 is a left end elevational view of FIG. 1.

I claim:

The ornamental design for a spatula for fill-in compositions, substantially as shown and described.
